UNITED STATES PATENT OFFICE.

ORLAND L. IHRIG, OF LOS ANGELES, CALIFORNIA.

HUMIDIFIER ATTACHMENT FOR CARBURETERS.

1,355,094.

Specification of Letters Patent.

Patented Oct. 5, 1920.

Application filed April 1, 1918. Serial No. 226,101.

To all whom it may concern:

Be it known that I, ORLAND L. IHRIG, a citizen of the United States, residing at Los Angeles, in the county of Los Angeles and State of California, have invented new and useful Improvements in Humidifier Attachments for Carbureters, of which the following is a specification.

My invention relates to improvements in humidifier attachment for carbureters in which means is provided for admitting water to the gaseous mixture passing through the carbureter to the engine cylinders and an object of my invention is to provide a humidifier attachment carrying a supply of water at a constant level from which supply the water is drawn into the carbureter by the influence of the air traffic through the carbureter; a second object being to so combine the humidifier attachment with the mixture passage of the carbureter that the amount of water drawn into the mixture will be governed by the volume of the mixture admitted to the cylinders.

The invention consists of the novel features herein shown, described and claimed.

Figure 1 is a side elevation of a carbureter in section and showing the attachment, embodying the principles of my invention, in section, and in working position relative to the carbureter.

Fig. 2 is an elevation of the device partly in section and looked at in the direction of the arrow 2, Fig. 1.

Fig. 3 is a top view of the humidifier and carbureter as shown in elevation in Figs. 1 and 2.

Fig. 4 is a horizontal sectional view of the humidifier and carbureter taken on the line 4-4, Fig. 1.

In carrying out my invention a carbureter 1 is provided comprising an air inlet passage 2, a fuel nozzle 3, a venturi 4, a mixture passage 5, and an auxiliary air passage 6.

At the side of the air passage is positioned a fuel chamber in which is mounted the conventional fuel bowl and float 7 for operating a needle valve (not shown). The fuel enters the carbureter by the tube 8 and passes to the fuel nozzle 3 through the conduit 9. Within the mixture passage 5 and above the venturi is mounted a throttle valve 10.

Mounted above the fuel chamber 7 and

at the side of the mixture passage 5 is a 55 humidifier attachment 11, the details of which are as follows:

A water bowl or chamber 12 is provided in which is positioned a float 13. The chamber 12 is provided with a cover 14 from 60 which depends an ear 15 carrying a pin upon which is pivoted a lever 16 having a cross bar 17, the lever being operated vertically by the float 13 by means of the bar 17.

In the cover 14 is formed a water inlet 65 conduit 18 communicating with the chamber 12. A needle valve 19 is mounted upon the end of the lever 16 and adapted to operate upon the water inlet orifice on the under side of the cover 14, thus controlling the 70 amount of water passing into the chamber 12.

The cover 14 is also adapted to fit against the side of the mixture passage 5 and has a port 20 leading from about the center of 75 the cover and connecting with a port cut through the wall of the mixture passage 5 just below the seat of the valve 10. A glass 21 is positioned above the outer terminus of the port 20 and is provided with a bonnet 80 or valve fitting 22 having a downwardly extending central nozzle 23. A valve 24 is mounted in the top of the bonnet 22 adapted to operate to govern the flow of fluid through the nozzle. A suction conduit 25 85 connects the nozzle 23 with the chamber 12 below the water level thus forming a sight feed means for the water passing from the supply chamber 12 to the mixture passage 5.

A vent 26 is provided for the bonnet 22 90 and a second vent 27 opens into the port 20 its opening being controlled by a valve 28.

The practical operation of the device is as follows: The valve 10 swings in the path of the dotted lines shown in Fig. 1 and in 95 its opening swings across the port 20. When the valve 10 is closed no water is drawn from the humidifier but as the valve is opened the port 20 begins to be exposed to the suction of the cylinders and water is 100 drawn from the chamber 12 through the conduit 25 past the valve 24 issuing in sight from the nozzle 23 and passing into the mixture through the port 20.

When the port 20 has been fully exposed 105 to the air traffic by a further opening of the valve 10 the amount of water then drawn in with the mixture is governed by the speed

of the engine or rather the vacuum created in the mixture passage due to the engine speed.

Thus I have provided a humidifying means for carburetors which is automatically controlled by the fluctuation of the volume of explosive mixture drawn into the engine cylinders which volume is the only criterion of the amount of moisture required 10 after a proper adjustment of the valve 24.

Various changes may be made in the invention as set forth herein in its preferred form without departing from the spirit of the invention, as claimed.

15 I claim:

1. A humidifier attachment for carburetors comprising a water bowl, a float mounted in the bowl, a cap forming a cover for the bowl, a lever pivotally connected to the 20 cap and resting upon the float, a water supply passage formed in the cap having a downwardly extending terminus opening into the bowl, and a needle valve mounted upon the free end of the lever pointing upwardly and adapted to operate to close the 25 inner terminus of the water supply passage.

2. A humidifier comprising a water bowl, a float operatively mounted in the bowl, a cap forming a cover for the water bowl, a 30 lever pivotally mounted above the float and resting upon the float, a boss formed integral with the cap, a water pipe tapped into the boss, there being a passage leading from the water pipe through the boss into the 35 bowl, a valve seat surrounding the inner terminus of the passage, and a valve controlling said valve seat, said valve being operatively connected to the free end of the lever.

40 3. A humidifier comprising a water bowl, a float operatively mounted in the bowl, a cap forming a cover for the water bowl, a lever pivotally mounted above the float and resting upon the float, a water supply 45 passage formed in the cap having an inner terminus opening into the bowl the terminus

being surrounded by a valve seat, a plunger having a needle point fitting the valve seat, the lower end of the plunger being connected to the free end of the lever so as to control 50 the flow of water into the bowl, a boss upon the cap and having a horizontal passage leading from its outer end to the center of the cap and having an upturned end at the center of the cap, a seat around the upturned 55 end of the passage, a glass tube upon the seat, a valve fitting upon the glass tube, a valve in the valve fitting for controlling an orifice discharging downwardly at the center of the glass tube, a pipe extending from 60 the valve fitting outwardly and downwardly through the cap and into the chamber of the water bowl, the lower end of the pipe being below the water level, and means for connecting the outer end of the passage to 65 the neck of a carburetor so as to discharge into the fuel mixture chamber below the throttle.

4. A humidifier comprising a water bowl, a float operated valve, means for supplying 70 water to the water bowl controlled by said valve, a cap forming a cover for the water bowl, a boss upon the cap having a horizontal passage leading from its outer end to the center of the cap and having an upturned end at the center of the cap, a seat around the upturned end of the passage, a glass tube upon the seat, a valve fitting upon the glass tube, a valve in the valve fitting for controlling an orifice discharging 75 80 downwardly at the center of the glass tube, a pipe extending from the valve fitting outwardly and downwardly through the cap and into the water bowl, the lower end of the pipe being below the water level, and means for connecting the outer end of the passage 85 to the neck of the carburetor so as to discharge into the fuel mixture chamber below the low side of the throttle.

In testimony whereof I have signed my 90 name to this specification.

ORLAND L. IHRIG.
